RAZOR BLADE HOLDER

Magnus Turnquist, Chicago, Ill.

Application March 15, 1934, Serial No. 715,689

4 Claims. (CL 51—216)

This invention relates to improvements in razor blade holders; and more particularly to means for properly holding a safety razor blade during the sharpening operation.

5 One of the main objects of this invention is to provide a safety razor blade holding device which is economically and simply arranged so that it can be produced at a very small cost, and whereby the blade can be readily and 10 properly sharpened on a hone or the like.

Another object is to provide an efficient razor blade holder which is so arranged that when it is placed on the sharpening member, it will automatically be tilted at the proper angle 15 thereon, and as it is drawn over the face of said member in the sharpening operation it will furthermore have its forward edge bearing on the face of the sharpening member, at the proper inclination, so that it will be drawn 20 against said forward edge and will be properly sharpened in its movement over said member.

A further object is to provide a blade holder which comprises a minimum of parts, preferably only one or two members, and which can be 25 readily made, as by stamping it from sheet metal, so as to reduce the cost of the holder to a minimum, and enable the purchase thereof by all.

A still further object is to furnish such a 30 blade holder with replaceable shoe means on its tilting means, to provide for extended wear and life of this device.

These and other objects and advantages will 35 become apparent from the following description, taken in connection with the accompanying drawing in which my invention is illustrated in several of its preferred forms, it being apparent that various other arrangements and forms of construction may be resorted to for 40 carrying out the objects and purposes of this invention.

In the drawing:

Fig. 1 is an inverted plan view illustrating an embodiment of my invention in its preferred 45 form of construction, including a pair of flange elements extending along the lower parts of the holder and serving as means for holding and for tilting the blade.

Fig. 2 is a side view of this form of holder.

50 Fig. 3 is a plan view thereof.

Fig. 4 is a cross-sectional view, taken on line 4—4 of Fig. 3, illustrating the automatic tilting of the holder and blade on the sharpening member.

55 Fig. 5 is a side view of a slightly modified

form, having the lower flange elements partly omitted, thereby providing a plurality of tilting elements or lugs.

Fig. 6 is an inverted plan view of this form.

Fig. 7 is a vertical sectional view illustrating my auxiliary wearing shoe applied to a holder, and it may be applied to either one of the above forms of holder.

Fig. 8 is a perspective view of the holder per se.

Fig. 9 is an inverted plan view of a further modified form of holder.

Fig. 10 is a side view thereof.

Fig. 11 is a cross-sectional view, taken on line 11—11 of Fig. 9.

The drawing illustrates my invention embodied in a few of its various forms of construction. In each form as shown the whole device consists of only one member or two members.

The form of device illustrated in Figs. 1 to 4 inclusive, comprises a handle member 15 which is provided with holding elements 16 on the lower part, adapted to extend through openings or slot means 17 provided intermediate the cutting edges of a razor blade 18, of the usual type, so as to hold the blade thereon. These elements are extended a short distance below the blade, and their lower end parts 19 are adapted to bear on the sharpening face or top 20 of a sharpening member 21, as a hone for example. They are of such a length and are so placed that they will cause the holder and the blade to automatically tilt at the proper angle upon said face 20, so as to place the cutting edge 22 of the blade in the proper sharpening position, as indicated in Fig. 4 of the drawing; in order that when the holder and blade are drawn to and fro over the face of the sharpening member the forwardly moving edge of the blade is placed to bear on said face and it will be drawn and sharpened against the edge, thereby providing for the proper and prompt sharpening of the blade.

For the sake of economy and simplicity this holder is preferably made from sheet material, such as sheet metal and the like, which is slightly resilient. It is preferably cut and bent to include an upper yoke-like portion 24 and lower inwardly bent portions 25 thereon which are brought closely together and have the pair 50 of holding elements 16 extending or projecting downwardly from their two adjacent end portions.

In this form of construction the elements 16 are arranged in the shape of a pair of flange 55

means which extend substantially the length of the adjacent ends of the two portions 25, as best shown in Fig. 2, and which, due to the resiliency of the material, are normally held 5 slightly spaced, as indicated by dotted lines in Fig. 4, so that they will resiliently but firmly hold the razor blade in position against said portions 25.

The yoke part 24 is preferably also provided 10 with apertures 26 therein, to furnish a better hold for the fingers in handling the device.

The form of construction shown in Figs. 5 and 6 is substantially like the above form, and includes the yoke 24' with the lower portions 25' 15 thereon, but the flange means or holding elements on this form are not continuous but partly cut-away, thereby forming a plurality of narrow lugs or holding fingers 16' on each lower portion 25'. This form is thereby adapted to suit 20 a razor blade 27 which has openings or slots 28 provided adjacent its two ends, instead of a complete slot extending through the main portion of the blade.

A wearing member or shoe 30 may also be 25 provided which is preferably channel shaped, as indicated in Figs. 7 and 8, having upwardly and inwardly curved flange portions 31 thereon, whereby it can be readily mounted on the elements 16, and likewise on the elements 16', of 30 the two above forms of holder, by pressing said elements tightly together in applying the shoe and also by sliding the shoe lengthwise on said elements. The shoe will take the wear in its movement over the sharpening member, and is especially useful when said elements have 35 been slightly worn down, being removable and readily replaceable and substantially inexpensive.

A further modified form of this invention is 40 illustrated in Figs. 9, 10, and 11 of the drawing. This form of device comprises a member 33, which is preferably arranged in the shape of a doubled-over strap adapted to engage over the intermediate part of blade 18 to clasp and hold 45 the same firmly in position. It serves the compound purpose of a holding member, and a tilting member and also of a wearing member or shoe.

The handle 34 in this form is preferably also 50 yoke-shaped and it has holding fingers 35 on its lower end provided with a pocket or seat 36 therebetween. The holding fingers are adapted to extend through the openings 17 in the blade, and the strap 33 is placed between the fingers 55 and within the seat, being tightly engaged and firmly held in position by said fingers.

In this form of construction the strap means 33 is inexpensive and is readily replaceable when worn, and the blade tilts upon this strap means,

so as to properly slant the blade and place the forwardly moving edge thereof in contact with the sharpening member during the sharpening operation, in a manner similar to that described above.

I claim:

1. A razor blade holder consisting of a yoke-shaped plate including upper handle arms provided with holding elements on the lower ends which are extendible through openings in a razor 10 blade and being flexible to resiliently engage the blade for fully supporting and retaining it in position on the ends of the arms, said elements extending a short distance below the razor blade and serving the dual function of 15 holding the blade in position and acting as wearing means adapted to bear on a substantially level face of a sharpening member, thereby facilitating tilting and sharpening the blade thereon in the sharpening operation. 20

2. A razor blade holder consisting of a single member of bent resilient sheet material which includes a yoke-shaped handle having flange elements on the end of its yoke portions normally held spaced and the lower part is adapted 25 to extend through openings provided in a razor blade, for resiliently holding the blade in position thereon, said elements extending below the blade and being adapted to bear on the sharpening member and tilt the blade in the sharp- 30 ening operation.

3. A razor blade holder comprising a doubled-over single strap member providing two spaced straps adapted to clasp a blade therebetween and to have its outer strap bear on the face of 35 a sharpening member for tilting the blade thereon, and handle means extending from the inner strap having projecting elements adapted to extend through openings in the blade and to clasp said strap member, whereby the blade 40 is readily tilted in drawing it over said member.

4. A razor blade holder consisting of a doubled strap of sheet metal adapted to clasp a razor blade therebetween and to bear on the face of a 45 sharpening member and tilt the blade thereon, and handle means of bent sheet metal having projecting elements on its lower ends and having indented seat means provided therebetween, said elements extending through openings in a 50 razor blade and said strap member being chiefly seated in said seat means and securely held between said elements, whereby the blade is automatically tilted while said strap bears on said sharpening member and the edges are alternately 55 sharpened by drawing the holder and blade to and fro over the face of said member.

MAGNUS TURNQUIST.
